UNITED STATES PATENT OFFICE.

HIRAM S. JACOBS, OF PORTLAND, OREGON.

IMPROVED WHEEL-DRESSING MACHINE.

Specification forming part of Letters Patent No. 40,004, dated September 15, 1863.

To all whom it may concern:

Be it known that I, HIRAM S. JACOBS, of Portland, in the county of Multnomah and State of Oregon, have invented a certain new and Improved Machine for Dressing the Rims and Reaming the Hubs of Wheels; and I do hereby declare the following to be a full and exact description of the same, reference being had to the accompanying drawings, making part of this specification, in which—

Figure 1 is a plan or top view of my improved machine. Fig. 2 is a side elevation thereof. Fig. 3 is a vertical section of the same in the line $x\ x$, Fig. 1. Fig. 4 is a vertical section in the line $y\ y$, Fig. 1. Fig. 5 is a section of a portion of the same taken in the line $z\ z$, Fig. 1. Fig. 6 is a plan of that portion of the mechanism of which Fig. 5 is a section. Fig. 7 is a vertical section taken in the line $w\ w$, Fig. 1.

The nature of my said invention consists, first, in a peculiar device for securing or chucking the wheel; second, in means for dressing the rim of the wheel; third, in means for reaming the hub; fourth, in a provision for adapting the machine to operate on wheels of any size; fifth, in means for dressing the face and back of the rim to any desired bevels.

In order that others skilled in the art to which my invention appertains may be enabled to fully understand and use the same, I will proceed to describe its construction and operation.

A A represent various parts of a strong frame, in which the several operating parts of the machine are to be supported and run.

B represents a hollow shaft, which is journaled in the cross-pieces B' B'. On the inner end of this shaft B a concave face-plate or chuck, C, is keyed so as to revolve therewith.

D represents one of a series of thumb-screws, each working upon the screw-threaded shank of a strong metallic hook or clamp, D', passing through corresponding orifices in the rim of the face plate, C.

B² represents a pin employed to center the wheel, (shown by red lines in Fig. 2,) and adapted to slide longitudinally within the hollow shaft B, for the purpose to be herein-after explained. The end b of the pin B² is caused to project beyond the inner end of the shaft B when said screw is not held by the set-screw b' by a spiral spring, b². The screw

b' serves to firmly hold the pin B² in its forward position while a wheel is being adjusted and secured to the face-plate.

E represents a drum secured to a hollow shaft, e, which is journaled in the standards A' A', rising from the frame A. To each end of the hollow shaft e is secured a pulley, E' E², on the outside of the standards A'. f is a shaft running within the hollow shaft e, and carrying at each end a pulley, F F'.

F² is a loose pulley turning on the shaft f, between the pulleys F and E'.

G is a sliding table running in guideways G', of segmental form, concentric with the drum E. Upon the said table are mounted rotary cutters H' H² H³, all driven by belts e' e² e³ from the drum E through the medium of drums h' h² h³ on the shafts of the said cutters. The side cutters, H' H², are employed to dress the face and back of the wheel-rim, and to adapt them for rims of various thickness are made adjustable in their distance asunder by means of crank-screws h⁴ h⁴ moving the cutter frames back and forth in guideways h⁵. The said guideways are also made adjustable on a vertical axis by means of segmental slots and clamp-screws h⁶, in order to adapt the cutters to dress the front and back of the wheel independently to any desired bevels. The cutter H³ is employed to dress the tread of the rim, and has a circular adjustment by like means with the face and back cutters, H' H². The action of the cutters upon the wheel is clearly illustrated in the vertical sectional view, Fig. 5, and by the horizontal section, Fig. 6, the rim of the wheel being shown in red.

The table G may be moved in either direction to place the cutters in contact with the rim of the wheel and remove them therefrom by means of a crank-shaft, I, bevel-pinion i i', transverse shaft I', pinion J, and rack j, or by a screw and pivoted nut, or by other suitable means.

Motion is communicated to the hollow shaft B of the face-plate C by a belt, K, from the pulley E², working on a pulley, k, on the shaft k', and acting through a suit of diminishing wheels k² k³ k⁴ k⁵, so as to impart a slow rotary motion to the face-plate and the wheel secured thereto while the cutters are rapidly rotated. The said gearing k² k³ k⁴ k⁵ works in a sliding frame, K², which may be moved

in either direction by a lever, L, and rack and pinion l to throw the pinion h^5 into or out of gear with the wheel b^3 on the hollow shaft B.

b^4 is a second cog-wheel on the hollow shaft B, which receives motion from the pulley F' of the center shaft, f, through a band, f', pulley F³, and pinion f², when it is necessary to rotate the wheel at a higher velocity for the purpose of reaming the hub.

M represents the reamer fixed in a stock, N, adapted to slide in guideways n n, and advanced or retracted by a rack and pinion, o, or other suitable means.

P may represent the main driving-belt.

Operation: The wheel is centered upon the face-plate by means of the pin B², and is then secured in correct position by the clamp-hooks D'. The driving-belt P being placed upon the pulley F', as shown in Fig. 3, motion is communicated to the drum E, and thereby to the cutters H' H² H³, the said cutters having been set to the required distance and angles. The pinion h^5 being then thrown into gear with the wheel b^3 , a slow rotary motion is communicated to the wheel clamped upon the face-plate. The table G is then drawn forward in manner already explained, in order to place the cutters in contact with the rim of the wheel, and the latter is dressed off with rapidity and accuracy to the form required, a single revolution of the wheel sufficing to dress its rim. This done, the cutters are moved back and the reamer M, being advanced within the aperture in the hub, the pinion h^5 is again thrown out of gear and a more rapid motion imparted to the wheel by throwing the driving-belt f' onto the pulley F on the shaft f. By this means the hub is quickly reamed out, and, as its position upon the face-plate has not been changed, it follows, of necessity that the aperture formed in the hub for the reception of the box must be accurately concentric with the tread of the wheel. The sliding pin B recedes within the shaft B to admit the reamer into the hub, and on the reamer being withdrawn the said pin is thrown out automatically by the spring b² in position ready for centering another wheel.

The ways G' being concentric with the drum

E, the tension upon the belts e' e² e³ will be the same in all positions of the table G, and hence the cutters will operate equally well upon a wheel of six feet in diameter, or one of two feet, or any required size.

It is well known that wheels are rarely made accurately true. For this reason the customary practice of chucking the wheel by the hub for finishing is objectionable and difficult in application; whereas by my mode of clamping the wheel to the face-plate by hooks applied at a distance from the center of the wheel I am enabled to draw the wheel straight and, working by the faces of the spokes, impart a symmetrical form to wheels originally imperfect.

Having thus described my invention, what I claim as new therein, and desire to secure by Letters Patent, is—

1. The concave face-plate C, provided with a centering-pin, B², and clamp-hooks D D', operating substantially as and for the purposes set forth.
2. The combination, with a suitable face-plate, of the cutters H' H² H³, driven simultaneously by bands from a common drum, E, in the manner and for the purposes explained.
3. The reamer M, carried by an advancing and receding stock, N, in the described combination with the yielding center-pin B², for the objects specified.
4. In combination with the cutters H' H² H³, driven by belts from a common drum, F, as explained, the sliding table G and segmental guides, by means of which the said cutters may be adjusted in the arc of a circle concentric with the said drum, in order to adapt the machine to operate on wheels of any size.
5. In combination with cutters H' H² H³, operated substantially in the manner explained, the use of guideways or bearings adjustable on vertical axes, in order to admit of dressing the face, back, and tread of the wheel to any required bevels.

HIRAM S. JACOBS.
